M. D. POTTER,
MATERNITY CORSET,
APPLICATION FILED JULY 11, 1919.

1,356,402.

Patented Oct. 19, 1920.

UNITED STATES PATENT OFFICE.

MABLE D. POTTER, OF BALTIMORE, MARYLAND.

MATERNITY-CORSET.

1,356,402.

Specification of Letters Patent. Patented Oct. 19, 1920.

Application filed July 11, 1919. Serial No. 310,268.

To all whom it may concern:

Be it known that I, Mrs. MABLE D. POTTER, a citizen of the United States, residing at Baltimore, Maryland, have invented certain new and useful Improvements in Maternity-Corsets; and I do hereby declare the following to be a full, clear, and exact description of the invention, such as will enable others skilled in the art to which it appertains to make and use the same.

This invention relates to women's wearing apparel and more particular to a maternity corset.

15 It is one of the objects of the present invention to provide an improved stay or corset construction, which is capable of a large range of adjustment and which also provides a substantial and comfortable support or stay and enables the adjustment of the same as may be required.

20 A further object of the invention is to provide a corset of few and simple elements which may be readily altered and adjusted to properly fit the body and at the same time provide a garment of this type which is free of cumbersome and uncomfortable elements.

With the above and other objects in view the invention consists of the construction, 30 the combination, and in details and arrangements of the parts as more particularly described hereinafter relative to the embodiment of the invention illustrated in the accompanying drawings, in which:

35 Figure 1 is a plan view of the outer surface of the garment.

Fig. 2 is a perspective view of a fragment of the lower front portion of the garment.

The garment comprises right and left 40 wings or main body portions indicated at 2 and 3 the adjacent edges of which are laced together as at 4, the laced portions forming the back of the garment. The top edge of each of the side pieces are provided with shoulder straps 5-5, which aid not only in supporting the garment but in maintaining it in supporting position when it is arranged about the body. The lateral vertical edges of the side members 2 and 3 may be fastened 45 together in the front of the body by any suitable means as for instance, by a series of eyes 6 extending for about two-thirds of the length of the front edge of the garment and terminating just below the lower end of the 55 edge rib 8. The garment fabric or body

extends below the lower end of the edge ribs 9-9 and is unstiffened so that it can be drawn snugly under and about the pit of the stomach and suitably fastened in effectual supporting position by any suitable means 60 here shown as comprising hooks and eyes 10. For the purpose of maintaining a garment in snug and effectual supporting position and yet allow it to automatically dis-tend or yield to conform to movements of 65 the body and thus reduce and obviate undesirable rigidity, the lower edge of the corset is made of elastic strips 11-11 which are here shown as connected to the lower ends of the back ribs 12 and the opposite ends of 70 these elastic strips are secured to portions 13.

To enable the increase in the circumferential length of the garment to fit bodies of different size the intermediate portions of 75 the side members 2-3 are slotted upwardly at 14-14 to a suitable height. The edges of the slits are provided with lacings 15, which may be opened or drawn together as the exigency requires. The slotted portions 14 may be overlapped on the inside, each by a fly or a tuck 16, thus effectually covering the slits, preventing the flesh from being pinched between the edge and unreasonably rubbed by the adjacent lacings. 85

One of the important features of the present invention is to provide means for assisting the garment in its abdominal supporting capacity and as here shown the lower front portions of the corset sides have attached flap pieces or tongues 18 to engage buckles 19 arranged on the adjacent ends of a girdle or strap 20 extended through suitable loops or keepers 21 formed on or attached to the outer surface of the corset and 95 extending across the back. The strap is prevented from shifting bodily around the waist and corset by being suitably fastened to the corset as by a line of stitches 22 located at the central portion of the back 100 of the belt and passing through the adjacent body structure of the corset.

What I desire to claim is:

1. A maternity corset comprising a front having stiffening stays at the meeting edges, 105 and pliant skirt portions extending below the stays, with means for interconnecting the edges, and a continuous supporting band extending across the back of the corset and connected at each end, respectively, to the 110

pliant skirt portions at the front of the corset.

2. A maternity corset comprising a front having stiffening stays at the meeting edges, 5 and pliant skirt portions extending below said stays, with means for interconnecting the edges, means in said skirt portions to permit of circumferential expansion, and an adjustable continuous supporting band 10 extending across the back and connected at each end, respectively, to the pliant skirt portions in front of said means to permit of circumferential expansion.

3. A maternity corset comprising a front 15 having stiffening stays at the meeting edges, and pliant skirt portions extending below said stays, with means for interconnecting the edges, and a continuous supporting band extending across the back and connected at 20 each end, respectively, to the pliant skirt portions at the front of the corset, and secured to the back of the corset at one line transverse of the band.

4. A maternity corset comprising a front

having stiffening stays at the meeting edges, 25 and pliant skirt portions extending below the stays, with means for interconnecting the edges, and a continuous supporting band extending across the back of the corset and connected at each end, respectively, to the 30 pliant skirt portions at the front of the corset, and keepers on the corset arranged to guide the band so that it will arch over the back of the wearer and sustain the weight of the abdomen.

5. A maternity corset comprising a front having stiffening stays at the meeting edges, 35 a pliant skirt portion extending below said stays with means for interconnecting the edges, and a continuing supporting band extending across the back, straps and buckles 40 for adjustably connecting the ends of said band to the said pliant skirt portion at the front of said corset, said band being secured to the back of the corset at one line trans- 45 verse of the band.

In testimony whereof I affix my signature.
MABLE D. POTTER.
